UNITED STATES PATENT OFFICE.

CHARLES H. LANPHIER, OF SPRINGFIELD, ILLINOIS.

METHOD AND APPARATUS FOR DETERMINING THE CALORIFIC VALUE OF GASES.

Application filed June 23, 1919. Serial No. 306,149.

To all whom it may concern:

Be it known that I, CHARLES H. LANPHIER, a citizen of the United States, residing at Springfield, county of Sangamon, and State 5 of Illinois, have invented certain new and useful Improvements in Methods and Apparatus for Determining the Calorific Value of Gases, of which the following is a specification.

10 My invention relates to a method and apparatus for determining the calorific value of gases, and the object of my invention is to provide such a method and apparatus for practically applying the method, whereby 15 the calorific value of a gas may be determined with relation to the calorific value of a gas of known quality. A further object of my invention is to provide an apparatus of the class mentioned by means of which 20 the value of the tested gas may be read directly in terms of any accepted standard thermal units.

The present invention is based upon and utilizes the known fact that the bright blue 25 flame of illuminating gas burned in a burner of the type known as the Bunsen burner indicates practically complete combustion resulting from an adequate supply of oxygen from the air, and that when the air supply 30 in the mixing chamber is insufficient a yellow tip will appear in the inner cone of the flame and will indicate incomplete combustion. In carrying out my invention, I introduce a gas of known calorific value, hereinafter 35 referred to as the laboratory gas, to a Bunsen burner, ignite the same, and then adjust the burner so that the yellow tip in the inner cone of the flame will just disappear, the parts of the burner which are provided with 40 graduations indicating standard thermal units having been previously set to correspond to the laboratory gas. I then shut off the supply of laboratory gas and introduce to the burner the gas to be tested, hereinafter 45 referred to as the commercial gas, and after igniting the same adjust the graduated portion of the burner until the luminous tip disappears. The reading of the graduations on the burner will then indicate the calorific 50 value of the gas being tested.

My invention will be more readily understood by reference to the accompanying drawings forming a part of this specification and in which,

55 Figure 1 is a vertical sectional view of the preferred form of apparatus embodying my

invention, portions of the device being shown in elevation.

Figure 2 is a horizontal section on the line 2—2 of Figure 1. 60

Figure 3 is a similar section on the line 3—3 of Figure 1.

Figure 4 is an elevation of a key used in calibrating the instrument, and

Figure 5 is a side elevation of a modified 65 form of the device.

Referring now to the drawings, 1 indicates the base of the device which is preferably cylindrical and supported upon suitable legs 2. In the upper part of the base 1 is an air 70 chamber 3 which is in communication with the atmosphere through a plurality of apertures 4. A closure 5 is provided for the upper end of the chamber and is preferably threaded into the upper end of the base as 75 indicated. A burner tube 6 has its lower end threaded into the base 1, as at 7, and extends upwardly through the chamber 3 and closure 5. An elongated aperture 9 is provided in the tube 6 within the chamber 80 3 for a purpose hereinafter described. A plug 10 is threaded into the lower end of the tube 6 and the base 1. This is provided with a bore 11 communicating with a passage 12 in the lower portion of the base, said 85 passage communicating with a supply pipe 13 for admitting gas to the apparatus. The upper end of the bore 11 of the plug 10 is reduced in diameter, terminating in a minute orifice 14 for the discharge of the gas into 90 the mixing chamber 15, the lower portion of the bore of the tube 6 comprising such chamber. A needle valve 16 controls the passage-way through the orifice 14 and has its stem threaded through the bottom of the base 1, 95 as indicated at 17. The stem of the needle valve terminates in a knurled head 18 to facilitate adjusting said valve. The upper end of the plug 10 is provided with mortises 19 to accommodate tenons 20 on the end of 100 a key 21. The key 21 is of greater length than the tube 6 so that the same may be inserted through said tube and used to adjust the plug 10 as will be described hereinafter.

Threaded upon the lower end of the tube 6 is a sleeve 22 which extends through the closure 5, forming a snug joint therewith, and is adapted to control the admission of air through the aperture 9 from the air chamber 3, it being obvious that as the sleeve 110 is screwed upwardly more air will be admitted, and as it is screwed downwardly

that the supply of air will be diminished.

The threads 23 between the tube 6 and sleeve 22 are preferably forty to the inch and the tube 6 above the upper end of the 5 sleeve 22 is provided with graduations 24 arranged forty to the inch, so that one complete revolution of the sleeve will raise or lower the same the distance of one graduation on the scale 24. The upper end of 10 the sleeve 22 is provided with a micrometer scale 25 which is divided into twenty-five equal parts, so that when the sleeve 22 is turned the distance between two adjacent 15 graduations on the micrometer scale, the sleeve will be moved upwardly or downwardly one one-thousandth of an inch. Each complete revolution of the sleeve will measure twenty-five B. T. U., and the rotation measured by one of the graduations 20 25 will measure one B. T. U.

By providing the chamber 3 surrounding the lower portion of the tube and sleeve, a shield is provided to protect the air inlet from drafts and dirt. It also permits the 25 air to enter the barrel or tube 6 at a uniform pressure and also prevents the hands of the operator from coming in contact with the end of the orifice or the bottom edge of the sleeve which would result in corrosion 30 and in time prevent proper and accurate operation of the device, as such corrosion would vary the size of the orifice. It also prevents mechanical damage to the said parts and also prevents sudden drafts of air 35 from causing the instrument to back fire, which in a short time would result in burning of the orifice and cause a wrong reading of the device.

In carrying out my method by means of 40 the apparatus above described, the said apparatus is first adjusted approximately to completely burn a gas of known calorific value. To this end, the sleeve 22 is screwed upwardly until the upper end thereof registers with the graduation indicating the calorific value of said laboratory gas, and then the plug 10 is screwed upwardly in the 45 base to reduce the opening 9 to a size which, as nearly as can be determined in advance, 50 is adapted to supply the right quantity of air for perfect combustion of the laboratory gas. The gas is then introduced through the pipe 13 and ignited at the upper end of the tube 6. If a yellow tip appears in the 55 inner flame cone, the needle valve is first regulated to adjust the supply of gas. When this reduces the supply of gas too much before the luminous tip disappears, the plug 10 must be screwed downwardly to 60 admit more air through the aperture 9. If, on the other hand, the yellow tip does not show in the inner cone flame, I first increase the gas supply by opening the needle valve until a faint yellow tip shows in the 65 inner flame cone; if, however, that adjust-

ment interferes with the full flame body, which should be about four inches in height, the plug 10 is screwed upwardly until the yellow tip appears in the inner flame cone and is then just eliminated by the method 70 above described. When the parts have been properly adjusted and the yellow tip has been just eliminated from the flame as described, the instrument will be ready to test the commercial gas. To do this the 75 commercial gas is introduced through the plug 10 and ignited at the upper end of the tube 6. The tube 22 is then screwed upwardly or downwardly as required until the luminous tip in the flame is just eliminated and 80 the reading of the instrument as before described will give the value of the commercial gas in terms of the thermal units indicated on the scales, in the form illustrated in B. T. U.

For illustration only, let it be assumed that the value of the standard gas has been found to be 500 B. T. U. and that the instrument has been adjusted and set accordingly, and that in testing the commercial gas 90 the yellow tip is visible in the inner cone of the flame, thus indicating that the calorific value of the commercial gas is greater than the calorific value of the laboratory or standard gas; and that to just eliminate the yellow tip the sleeve 22 has made two and one-fifth (2 $\frac{1}{5}$) counter-clockwise rotations, the one-fifth rotation being indicated by the numeral 5 of the scale 25, then the reading will be: 500 B. T. U. + 55 B. T. U. = 555 B. T. 95 U., the true value of the gas as compared with the standard. In the above example the commercial gas is 55 B. T. U. above the standard.

Reversely, if upon igniting the commercial 105 gas the yellow tip is not visible in the inner cone of the flame, the absence of the yellow tip will indicate that the calorific value of the commercial gas is no greater but preferably below the calorific value of the laboratory or standard gas. To find the true value 110 of the commercial gas compared with the standard gas: Assume as in the preceding example, that 500 B. T. U. is the calorific value of the laboratory or standard gas and that at the start the upper edge of the sleeve is at the graduation 500 of the scale 24. To test the commercial gas it will be necessary first to reduce the supply of air to such extent that the yellow tip will appear in the 120 inner cone of the flame and then gradually increase the supply of air just enough to eliminate the yellow tip and then note the readings of the scales 24 and 25.

Assume that the yellow tip has been just 125 eliminated and that on the scale 24 the reading is 450 units and on the scale 25 the reading is 5 units, then the calorific value of the tested gas would be the value of the standard gas, 500 B. T. U. - 55 B. T. U. = 130

445 B. T. U. and so on for the various tests which may occur in practice.

I have found by experiment that the length of Bunsen tube most suitable for a caloroptic of the preferred form is at least twelve times the diameter of the tube, because the gas and air traversing the unusual length of the tube become thoroughly diffused and mixed and consequently produce a more even and constant flame-body than could be produced by a tube in which the ratio of length to diameter is less than 12 to 1. I have also found by experiment that a minute gas orifice as compared with the area of the bore of the Bunsen tube,—in practice about 1 to 60—is best adapted to check the velocity of the air and gas mixture beyond the point of air admission and is also best adapted for use with a Bunsen tube of a length not less than twelve times the diameter of its bore.

In Figure 5, I have illustrated a slightly modified form of device in which 26 indicates the base, flared at the bottom, as at 27, forming an extended footing and a recess 28 into which extends the lower end of the adjusting screw 29 for the needle valve 16'. A plug 10' is threaded into the upper end of the base 26 and a gas inlet port 12' communicates with the device between the plug 10' and adjusting screw 29. The upper end of the base 26 is shouldered, as at 30, to receive the shell 31 forming a main admission chamber 32, said shell being provided with air admission ports 4'. The burner tube 6' is threaded into the base and threaded upon the same is the sleeve 22'. The lower end of the tube 6' is provided with the air admission port 9' which is controlled by sleeve 22' as in the foregoing modification. The operation of the device is identical with that of the afore-described form.

I claim:—

1. The method of measuring the calorific value of gas which consists in supplying a gas of known calorific value to a Bunsen burner, adjusting said burner until the flame becomes non-luminous, shutting off the supply of gas of known value, and introducing the gas to be tested, adjusting the burner to eliminate the luminous flame and noting the difference between the former and latter adjustments of the burner, substantially as described.

55 2. The method of measuring the calorific value of gas consisting of introducing the gas in a Bunsen burner previously adjusted to completely burn the gas of a known calorific value, adjusting the burner to eliminate

the luminous flame and noting the reading 60 on the graduated scale, substantially as described.

3. A device for measuring the calorific value of gases comprising a Bunsen burner, a sleeve threaded thereon and controlling the air admission port to said burner, there being co-operating graduations on said burner and said sleeve, substantially as described.

4. A device for measuring the calorific value of gases, comprising a Bunsen burner, 70 including a burner tube having a graduated scale extending longitudinally thereof, a sleeve threaded on said tube and controlling the air admission port to said burner, and the upper edge of said sleeve co-operating 75 with said scale, substantially as described.

5. A device as set forth in claim 4 further characterized by having graduations on the upper edge of said tube, as and for the purpose specified.

80 6. A device as set forth in claim 3, in combination with means for initially calibrating the instrument to a gas of known calorific value, substantially as described.

85 7. A device of the class described comprising a base provided with a gas admission passageway, a burner tube extending upwardly from said base and provided with an air admission port, an air chamber on said base surrounding the lower end of said tube, a sleeve threaded on said burner tube and controlling the air port therein, there being co-operating graduations on said sleeve and said tube, substantially as described.

90 8. A device as set forth in claim 7, in combination with a gas jet plug threaded in said base and extending into the lower end of said burner tube and adapted to vary the size of the air admission port in said tube, and a needle valve controlling the orifice in said 100 plug, substantially as described.

95 9. A device as set forth in claim 8 in which the cross sectional area of the orifice in said plug and the cross sectional area of the burner tube passageway are approximately proportionately in a ratio of 1 to 60.

100 10. A device as set forth in claim 7, in which the length of the tube is to its diameter in the ratio of not less than 12 to 1, substantially as described.

In testimony whereof I have signed my name to this specification in the presence of two subscribing witnesses.

CHARLES H. LANPHIER.
